UNITED STATES PATENT OFFICE.

WILLIAM E. STORMS, OF DETROIT, MICHIGAN, ASSIGNOR TO COLONIAL ELECTRIC CAR CO., OF DETROIT, MICHIGAN, A CORPORATION OF MICHIGAN.

DESIGN FOR A MOTOR-VEHICLE BODY.

43,329.

Specification for Design.

Patented Dec. 3, 1912.

Application filed October 16, 1911. Serial No. 655,084. Term of patent 3½ years.

To all whom it may concern:

Be it known that I, WILLIAM E. STORMS, a citizen of the United States of America, residing at Detroit, in the county of Wayne and State of Michigan, have invented a new, original, and ornamental Design for a Motor-Vehicle Body, of which the following is a specification, reference being had therein to the accompanying drawing, forming part thereof.

The figure is a perspective view of a

motor vehicle body, showing my new design.

I claim:

The ornamental design for a motor-vehicle body, as shown.

In testimony whereof I affix my signature in presence of two witnesses.

WILLIAM E. STORMS.

Witnesses:

OTTO F. BARTHEL,
L. C. MOORE.
